UNITED STATES PATENT OFFICE.

JOHN S. BUTTERFIELD, OF CHICAGO, ILLINOIS.

STOCK-CAR.

SPECIFICATION forming part of Letters Patent No. 252,863, dated January 31, 1882.

Application filed June 1, 1881. (No model.)

To all whom it may concern:

Be it known that I, JOHN S. BUTTERFIELD, of Chicago, Illinois, have invented certain new and useful Improvements in Stock-Cars; and 5 I do hereby declare that the following is a full, clear, and exact description thereof, reference being had to the accompanying drawings, and to the letters of reference marked thereon, which form a part of this specification.

10 This invention relates to devices concerned in feeding cattle on cars through side doors and from troughs located at stations along the railroad-line.

It consists in a trough provided with a rack 15 or guard rising from its rear part, combined with a car-door hinged at its upper edge and adapted to swing outward and upward, and to rest on the rack or guard so as to form with the trough and guard an inclosure guarding 20 the opening in the car.

It also consists in devices that will be more 25 fully described for connecting the lifting doors at both sides of the lateral entrance of the car with the lifting door in the slide which closes said entrance, so that all three may be opened or closed at once.

In the drawings, Figure 1 is a side elevation 30 of a cattle-car containing my improvements for simultaneously lifting the three feed doors. Fig. 2 is a fragmentary horizontal section through 2 of Fig. 1. Fig. 3 is an elevation of a detached slat of the side door over which the slide passes, showing a slot therein with a cross-piece which engages a hook-bolt on the 35 slide. Fig. 4 is a horizontal section, showing an alternative form of the hooking bolt or catch by which the lifting door of the slide engages the lifting door over which it moves when opened and closed. Fig. 5 is a side elevation 40 of the device shown in Fig. 4. Fig. 6 is an end view of a car and trough containing my improvement for inclosing the feed-opening when the doors are lifted.

A and A' are the stationary lifting doors of 45 the car, and B is the lifting door of the slide C. Said slide is here shown as opening to the right, and therefore as sliding outside the lifting door A'. The doors A and A' are here shown as respectively composed of the three 50 horizontal slats a a', connected by cleats or metal straps a'', pivoted at their upper ends to the uprights d of the car.

The lifting door B is shown as consisting of a rectangular frame, b, pivoted to and between the vertical frame-pieces c of the slide C. The 55 slide C runs back and forth in the usual ways or guides, and is arranged to just fairly clear the door A' when the latter is closed.

As means for connecting the three doors A, A', and B, so that they may be together lifted 60 or lowered, the door B has the fixed projecting bolt D, which, when the slide is being closed, enters the staple D', secured to the lower slat or slats a of the door A.

At the opposite end of the door B a hooked 65 bolt or catch is provided, preferably being the inwardly and backwardly curved extremity E of a long spring, E', secured to the lower framerrail, b, of the door B far enough from the end of the latter to allow the free extremity E to 70 spring outward and inward an inch, or thereabout. As a means of engaging the bolt proper or hook e of the catch E with the door A', the lower slat a' of the latter is provided with a slot, s, into which the hook or bolt e may drop 75 when the slide is nearly closed, and a fixed staple or cross-piece, e', covering the inner end of said slot s, beneath which the bolt e is finally drawn as the slide is thereafter completely closed. The outer end of the slot s and the 80 outer and under face of the catch E are beveled, as shown, so that when the slide is opened said catch will ride out of the slot s and along the face of the slat a'. When the bolt D is in engagement with the staple D' and the bolt e 85 with the cross-piece e' it is evident that by raising the door B both the doors A and A' will also be raised. It is also evident that the connections of the door B with the doors A and A' in no way prevent the movement of the 90 slide C.

Instead of the long spring E' having a catch consisting of the hooked end E, a catch may be hinged to the door B, as seen in Figs. 4 and 5, and a separate spring, E'', may be applied thereto as a means of throwing the catch into the slot s, as also shown in Figs. 4 and 5.

If preferred, and the position of the uprights d will allow, the catch E may be rigid with the door B, and its bolt e may run between the 100 slats a', in which case the staple or piece e' will be also located in or over the space between said slats; or the bolt e may still better run just below the lower slat, a', the staple e' being

appropriately located to engage the same when the slide is closed.

The hinges of the several doors A, A', and B are arranged in the same horizontal plane, 5 and as nearly as possible in the same vertical plane. Any necessary deviation from the latter may be allowed for in the width of the slot s or staples D' and e' relative to the width of the hook which engages the same, so that the hook may move crosswise in the staple a distance corresponding to the distance at which the hinges of B are set outward farther than those of A or A'.

In connection with a hinged hook-bolt, E, the 15 spring E² may be dispensed with, said hook being directed into the slot or beneath the loop e' by the person closing the door; but the spring is preferable, as giving automatic action to said bolt.

20 In Fig. 6 the entire door, composed of the sections A, A', and B, is shown raised, as in use when the cattle are fed from the trough T, located near the track at a feeding station. Said trough is supported in any approved manner, 25 but preferably by the means shown in Letters Patent recently granted to me—that is, by pivoted arms extended from fixed posts near the track. The trough is provided with rods p, set up in its rear and transverse end edges, and 30 connected by a top rail, p', thus forming a vertical open guard, G, surrounding the trough and reaching preferably about as high as the door-hinges. The door being lifted to a suitable height, the trough is advanced to the car- 35 side, as shown, when the door is let fall upon the guard G, forming therewith and with the trough a perfect inclosure covering the door-opening. In the case of the smaller stock, such an inclosure by its presence or appearance only 40 will suffice to deter the animals from any attempt to escape which they might in its absence be led to make through the open door.

The guard may include an inner set of rods, p², behind which fodder may be held for the stock; or said guard may consist of a close or 45 a slotted rail of proper height, as may be preferred.

I claim as my invention—

1. In combination with the stationary lifting doors A and A' and the similarly-lifting door 50 B of the slide C, the bolts D and e and the staples D' and e', applied to the several parts, as shown and described, and for the purposes set forth.

2. As a means of engaging the lifting door 55 B of the slide C with the lifting door A', over which the slide runs, the hooked head or catch E e and the staple e', applied to the respective parts, and operating substantially as set forth.

3. The outwardly and inwardly movable 60 catch E e, applied to the lifting door B of the slide C, combined with the lifting door A', having the slot s and staple e, substantially as described, and for the purposes specified.

4. The combination, with the door A', having a slot, s, and staple e', the door B of the slide C, provided with a movable part, E, provided with the bolt e, and with a spring whereby the bolt is borne inward so as to pass beneath the staple, substantially as set forth. 70

5. In combination with the outwardly and inwardly swinging door of the car, the external trough, T, having the rack or guard G, whereby the trough, rack, and door may together constitute an inclosure over the door-opening, substantially as described. 75

In testimony that I claim the foregoing as my invention I affix my signature in presence of two witnesses.

JOHN S. BUTTERFIELD.
